Primary Examiner — T Chase Nelson*Assistant Examiner* — Jonathan J. Han(74) *Attorney, Agent, or Firm* — Christensen, Fonder,
Dardi & Herbert PLLC(57) **CLAIM**

We claim the ornamental design for a buckle for a rifle sling, as shown and described.

DESCRIPTION

FIG. 1 is a perspective view of a buckle for a rifle sling according to the invention.

FIG. 2 is a front view of a buckle for a rifle sling according to the invention.

FIG. 3 is a rear view of a buckle for a rifle sling according to the invention.

FIG. 4 is a top view of a buckle for a rifle sling according to the invention.

FIG. 5 is a bottom view of a buckle for a rifle sling according to the invention.

FIG. 6 is a right side view of a buckle for a rifle sling according to the invention; and,

FIG. 7 is a left side view of a buckle for a rifle sling according to the invention.
